UNITED STATES PATENT OFFICE

162,206

COMBINATION TABLE AND RANGE

Richard W. Merkle, Edwardsville, Ill., assignor to
The Medart Company, St. Louis, Mo., a corporation of Missouri

Application July 3, 1950, Serial No. 10,946

Term of patent 14 years

(Cl. D33—14)

To all whom it may concern:

Be it known that I, Richard W. Merkle, a citizen of the United States and a resident of the city of Edwardsville, county of Madison, and State of Illinois, have invented a new, original, and ornamental Design for a Combination Table and Range, of which the following is a specification, reference being had to the accompanying drawing, forming part thereof.

Fig. 1 is a perspective view showing my new design for a combination table and range and,

Fig. 2 is a perspective view similar to that of Fig. 1 showing the range exposed for use.

I claim:

The ornamental design for a combination table and range, substantially as shown and described.
RICHARD W. MERKLE.
